G. JUER

METHOD OF NITRATING CELLULOSE

Filed June 5, 1923

Patented Nov. 17, 1925.

1,562,093

UNITED STATES PATENT OFFICE.

GEORGE JUER, OF HOPEWELL, VIRGINIA, ASSIGNOR TO TUBIZE ARTIFICIAL SILK COMPANY OF AMERICA, A CORPORATION OF DELAWARE.

METHOD OF NITRATING CELLULOSE.

Application filed June 5, 1923. Serial No. 643,548.

To all whom it may concern:

Be it known that I, GEORGE JUER, recently a subject of the former Austro-Hungarian Empire, and now a resident of Hopewell, 5 in the county of Prince George, in the State of Virginia, have invented certain new and useful Improvements in Methods of Nitrating Cellulose, of which the following is a true and exact description, reference being 10 had to the accompanying drawing, which forms a part thereof.

My invention relates to the nitration of cellulose, ordinarily cotton. As heretofore carried on, this operation has been effected 15 in mixing pots into which the cotton and the acids are fed together and in which they are thoroughly mixed, the different batches remaining in the mixing pots until the nitration is complete, that is to say, until the cotton 20 ton and the acid ceases to react upon each other. Prolonged mixing during the nitration operation is found to have a tendency to break the cotton which is highly detrimental to the subsequent handling of the nitrated 25 material while, if the mixing is not continued, uniform nitration is apt to be impaired owing to the tendency of the cotton to sink to the bottom of the pot and of the acids to form layers of different density. 30 The object of my invention is to provide a method in which the nitration of the cotton can take place with great uniformity, with all necessary and the least harmful mixing of the batch and in a plant of great compactness and simplicity requiring much less 35 labor in its operation than has heretofore been necessary. My method consists, broadly speaking, in mixing batches of cellulose and acids in mixing pots and in the ordinary 40 way and then charging the partly nitrated batch into a rotatable horizontal cylinder by the rotation of which, preferably occurring at intervals and not continuously, the batch is tumbled so as to effect the necessary mixing 45 of the acids and cellulose in the gentlest and least injurious way until the nitration is complete.

By preference and for the best results I employ a long horizontal cylinder, the bottom 50 of which is divided into chambers of sufficient capacity to hold and keep entirely separate the different batches successively charged in the cylinder by a spiral web riveted to the inside of the cylinder of such 55 height and so spaced as to provide bottom

chambers of a holding capacity of from three to four times the bulk of the batch. In this apparatus, which forms the subject matter of my Letters Patent No. 1,485,507, 60 March 4, 1924, the cylinder is rotated intermittently between the delivery to it of batches from the mixing pot and each batch is contained in the cylinder and intermittently tumbled as described for a sufficient time to effect complete nitration. My invention will be best understood as described 65 in connection with the drawing which illustrates an apparatus adapted for its practice, the drawing being an elevation for the most part in section.

A indicates the flooring of a room at a higher elevation than the nitrating apparatus in which the cotton to be nitrated is stored and from which leads a hopper B provided with a feeding device indicated at 70 C. B' indicates the delivery end of the hopper opening as shown into a hood D which extends over the top of the mixing pot. D' is an opening in the top of the hood through which the shaft of the mixing device extends. D² is an opening in the hood 75 through which an acid pipe is introduced into the hood and D³ is a pipe or conduit leading from the hood and connected with a fan, not shown, for drawing off the acid 80 fumes which rise in the hood from the mixing pot. E indicates the housing for the mixing apparatus, E' indicating a driving shaft which, as shown, is connected by a mitre wheel E² and the mitre wheel E³ with 85 the shaft E⁴ which through a mitre gear E⁵ drives a mitre gear E⁶ from which extends a shaft E⁷ connected so as to rotate with the gear E⁶ but free to move up and down in it, the lower part of this shaft being threaded 90 as indicated at E⁸ and the threaded portion of the shaft being engaged with a threaded portion E⁹ of the housing E. E¹⁰ indicates the mixing wheel supported at the bottom of the shaft E⁷. This part of the apparatus is not new with me and is not shown 95 in detail. It will be understood that the shaft E⁴ is rotated alternately in opposite directions so that the mixing device E¹⁰ also rotating in opposite directions will alternately rise and fall in its downward movement pressing the cotton entering the hood through the hopper into the mixing pot and while in the pot acting to mix the cotton 100 thoroughly with the acid.

F is a measuring tank for the acid from which leads a pipe F' for delivering the acid into the mixing pot, F² indicating a cap for opening and closing this pipe. G is a platform on which are supported the standards G' which support the trunnions H' of the mixing pot indicated at H. I is a hopper secured in the end of the cylinder J and opening into the cylinder through its lower end indicated at I'. I² is a closure for the hopper which is opened when the charge is being dumped into it from the mixing pot and which should remain closed during the rotating movement of the cylinder. J is the cylinder to the inner wall of which is secured the helically bent plate indicated at J'. The depth and pitch of this helix should be such as will divide the lower portion of the cylinder into a series of containing chambers indicated in the drawing by the numerals from 1 to 12 and each of such dimension as to hold and keep separate a charge delivered into the cylinder from the mixing pot. I consider it advisable that each chamber, 1, 2, etc., should have a capacity of about three times that of the mixing pot. The end of the helix indicated at J² is formed so as to lead directly into the delivery passage J³ at the rear end of the cylinder. J⁴ and J⁵ are circular rings or bearings secured to the cylinder J and through which it is supported on rollers indicated at J⁷ and J⁸. J⁶ is an annular rack or gear wheel secured to the cylinder J and engaged with the pinion J⁹ on a shaft J¹⁰ to which, as shown, are secured fast and loose pulleys J¹¹ and J¹². K is a delivery conduit with which the delivery end J³ of the cylinder connects as shown and which leads into a centrifugal wringer indicated at L and which may be of ordinarily used construction from which the dried nitrate of cotton is delivered into a storage chamber M. N is a conduit leading from the upper end of the delivery conduit K to a fan indicated at N', from which leads an outlet conduit N².

In operation a measured charge of acid is delivered into the mixing pot H and a measured charge of cotton is dumped into the hopper B. The feeding device C and mixing device E¹⁰ are then set in operation, the cotton being fed with uniform determined speed into the mixing pot and the mixer E¹⁰ in its downward movement pressing the cotton which has passed the delivery end B' of the hopper down into the mixing pot H and thoroughly stirring it into the

acid. When the full charge of cotton has been delivered into the mixing pot and thoroughly mixed with the acid therein the cylinder J brought to the position shown in the drawing with its hopper I in proper position to receive the charge from the mixing pot has the contents of the mixing pot dumped into it, the charge occupying the divisional chamber indicated at 1 and thereafter the cylinder J is rotated through one complete revolution so that the charge just dumped into it will occupy the chamber indicated at 2. A new charge of acid and cotton is then mixed in the mixing pot and dumped into the chamber 1 of the cylinder J and so on. The number of chambers into which the cylinder J is divided by the spirally twisted plate is such as to insure that each charge progressively delivered to the cylinder and progressively moved along the length of the cylinder should remain in the cylinder for a sufficient length of time to insure its complete nitration so that when the charges are delivered from the end chamber 12 into the outlet passage J³ and through the conduit K into the wringer L nitration will be completely effected.

It will be obvious that my mechanism is such that a single mixing pot and mixing apparatus can be kept in practically continuous operation to thoroughly mix the cotton and acid together and begin the nitrating operation while the greater part of the operation of nitration goes on in the mixing cylinder which keeps the charges from the mixing pot separated from each other and retains each charge for a sufficient length of time to insure the complete nitration of the cotton before delivering it to the drying apparatus.

The leading off of fumes from the hood over the mixing pot and from the conduit K is a detail of practical importance enabling my apparatus to be used without exposing the workmen to the acid fumes which arise from the mixing pot and cylinder.

Having now described my invention, what I claim as new and desire to secure by Letters Patent, is:

The method of nitrating cellulose which consists in thoroughly mixing cellulose and acids in a mixing pot so as to effect a partial nitration of the cellulose, charging the partially nitrated cellulose and admixed acids into a rotatable cylinder and tumbling the batch by rotating the cylinder until the nitration is complete.

GEORGE JUER.
